United States Patent Office

Des. 203,238

Patented Dec. 14, 1965

203,238

CIGARETTE HOLDER OR THE LIKE

Edith A. Kovacs, 2301 Bowmont Drive,
Beverly Hills, Calif.

Filed May 18, 1964, Ser. No. 80,012

Term of patent 14 years

(Cl. D85—8)

FIGURE 1 is a perspective view of a cigarette holder or the like embodying my new design;

FIGURE 5 is a perspective view of another embodiment of a cigarette holder or the like employing my new design in which the cigarette-holding portion is coplanar with the ring portion; having a U-shaped cigarette-holding portion attached to the narrowest portion thereof with each of the legs of the cigarette-holding portion having a width tapering outwardly away from its point of connection to the band.

I claim:

The ornamental design for a cigarette holder or the like, as shown and described.
